UNITED STATES PATENT OFFICE

EDWIN DORSEY LOANE, JR., OF BALTIMORE, MARYLAND.

INJECTOR.

1,162,789.

Specification of Letters Patent.

Patented Dec. 7, 1915.

Application filed March 24, 1908. Serial No. 423,065.

To all whom it may concern:

Be it known that I, EDWIN DORSEY LOANE, Jr., a citizen of the United States, residing at Baltimore city, in the State of Maryland, have invented a new and useful Injector, of which the following is a specification.

My invention relates to improvements in injectors which are mechanically operated; and the objects of my improvement are, first, to provide a means for automatically introducing a substance into a chamber under pressure by means of the pressure therein; second, the regulation of said injector whereby the pressure must reach a predetermined point in a chamber before said injector will introduce the substance therein; and, third, means of regulating the discharge from said injector. I attain these objects by the mechanism illustrated in the accompanying drawings in which—

Figure 1 is a sectional view of my improvement showing the various parts exposed; Fig. 2, is a view taken through "A B" of Fig. 1; and Fig. 3, is a sectional view of a modified form of my invention.

Similar numerals refer to similar parts throughout the several views.

1 is the casing, one end of which is threaded at 2 in order to be screwed into a chamber such as the head of a gasoline engine cylinder, the other end 3 of said casing being threaded to enable cap 4 to be screwed thereon. In cap 4 is adjusting screw 5 which is locked in position by jam nut 6. In the center of adjusting screw 5 is passage 7 communicating with space 8 through opening 9 thus putting space 8 in direct communication with the exterior.

10 is a piston working in casing 1 and to which is attached piston rod 11 which rod works in space 8. Piston 10 is hollow and has valve 12 therein which valve 12 is held in position by valve stem 13 and spring 14.

15 are openings communicating with the interior of piston 10 and are controlled by valve 12.

16 is a piston head and through which is passage 17 communicating with space 18.

19 is a spring tending to keep piston 10 and piston head 16 against shoulder 20.

21 is regulating block in which piston rod 11 works and which controls and limits the

movements of piston 10 and the pressure of spring 19.

22 is a suction opening or supply, to which 55 is attached a check valve and a pipe leading into the fluid to be injected.

23 is the suction chamber.

The operation of my invention is as follows:—Threaded portion 2 of casing 1 is 60 screwed into the chamber into which we desire to introduce the substance. I will specifically describe my invention as applied to a gasoline or oil engine but I do not wish to be understood as limiting myself to this 65 specific use. In Fig. 3 the fluid to be injected is drawn into chamber 23 and discharged through passage 17 into the cylinder when the pressure of combustion takes place forcing piston 10 against spring 19, 70 the discharge through passage 17 may be regulated by screw 24. If it is desired to introduce water into the gas engine cylinder after compression and ignition adjusting screw 5 is screwed against regulating block 75 21 until spring 19 is in such compression that piston 10 containing piston head 16 is not forced off or away from shoulder 20 by the pressure of compression in the cylinder and not until ignition takes place when the 80 pressure of combustion is available in space 18 for the purpose. At the pressure of combustion piston 10 is forced back allowing the fluid that is in space 23 to enter the piston through openings 15 and valve 12 and 85 through that to be squirted out of passage 17 the pressure on the two ends of piston 10 being unequal one end being the area of piston head 16 the other end being the same area less the area of the end of the piston 90 rod 11 which is exposed to the atmosphere through passage 7 and opening 9. As the pressure in space 18 is reduced piston 10 resumes its normal position drawing liquid into space 23 through supply 22 and pipe in 95 which an ordinary check valve 25 is placed, said pipe containing also a regulating valve 26, the length of piston rod 11 operating in space 8 being such that the desired amount of operation of piston 10 is allowed, this 100 stroke being regulated in the form shown in Fig. 2 by screw 5, the spring 19 being regulated by cap 4 which is shown screwed hard down in the figure. If it is desired to intro-

duce fuel such as gasoline, coal oil, petroleum or other burning fluid, the same may be introduced on the compression stroke of the engine before ignition by regulating 5 spring 19 so that piston 10 will operate at any desired position in the compression stroke.

Having thus described my invention what I claim and desire to secure by Letters Patent is—

- 10 1. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas, the end of larger area being exposed to the delivery pressure and 15 the end of smaller area being exposed to the pressure in the casing between the plunger and the supply, and yielding means moving the plunger toward the delivery.
- 20 2. An injector comprising a casing with means of supply adjacent to one end thereof and a delivery adjacent to the other end, a liquid supply pipe communicating with the supply, a check valve therein, a plunger in the casing between the supply and delivery 25 free to reciprocate therein and having ends of differential areas, the end of larger area being exposed to the delivery pressure, the end of smaller area being exposed to the pressure in the casing between the plunger 30 and the supply, and a portion thereof being exposed to a less pressure than the discharge pressure when the plunger in the casing is moving toward the supply end of the casing, and yielding means moving the plunger toward the delivery. 35
- 40 3. An injector comprising a casing with means of supply at one end thereof and a delivery at the other end, a liquid supply pipe communicating with the supply, a check valve therein, a plunger in the casing between the supply and delivery free to reciprocate therein having ends of differential areas the end of larger area being exposed to the delivery pressure the end of smaller 45 area being exposed to the pressure in the casing between the plunger and the supply and a portion thereof being exposed to a less pressure than the discharge pressure when the plunger in the casing is moving 50 toward the supply end of the casing, yielding means moving the plunger toward the delivery, and means of regulating the stroke of said plunger.
- 55 4. An injector comprising a casing with means of supply at one end thereof and a delivery at the other end, a liquid supply pipe communicating with the supply, a check valve therein, a plunger in the casing between the supply and delivery free to reciprocate therein and having ends of differential areas the end of larger area being exposed to the delivery pressure through the delivery and the smaller area being exposed to the pressure in the casing between the plunger and the supply, yielding means moving the plunger toward the delivery and means of regulating the said yielding means.
- 60 5. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas the end of larger area being exposed to the delivery pressure the end of smaller area being exposed to the pressure in the casing between the plunger and the supply, means of regulating the stroke of said plunger, means of maintaining the plunger 70 against the delivery pressure until a predetermined point of said pressure is reached and means of regulating said predetermined point of said pressure.
- 65 6. An injector comprising a casing with a supply adjacent to one end and a delivery adjacent to the other end, a liquid supply pipe communicating with the supply, a valve controlling said supply, a plunger in the casing between the supply and delivery free to reciprocate therein and having ends of differential areas the end of larger area being exposed to the delivery pressure the smaller area being exposed to the pressure in the casing between the plunger and the supply, yielding means moving the plunger toward the delivery and a valve controlling the delivery.
- 70 7. An automatic injector comprising a casing with means of supply at one end thereof and a delivery adjacent to the other end, a liquid supply pipe communicating with the supply, a valve controlling said supply, a delivery passage connecting the delivery end of said casing with the supply, a check valve controlling said passage, a plunger in the casing between the means of supply and delivery free to reciprocate therein and having ends of differential areas the end of larger area being exposed to the delivery pressure 100 the end of smaller area being exposed to the pressure in the casing between the plunger and the supply and a portion thereof being exposed to a less pressure than the delivery pressure when the plunger in the casing is moving toward the supply end of the casing, and yielding means moving the plunger toward the delivery. 105
- 75 8. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas the end of larger area being exposed to the delivery pressure through the delivery and the smaller area being exposed to the pressure in the casing between the plunger and the supply, yielding means moving the plunger toward the delivery and means of regulating the said yielding means.
- 80 9. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas the end of larger area being exposed to the delivery pressure the end of smaller area being exposed to the pressure in the casing between the plunger and the supply, means of regulating the stroke of said plunger, means of maintaining the plunger 110 against the delivery pressure until a predetermined point of said pressure is reached and means of regulating said predetermined point of said pressure.
- 85 10. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas the end of larger area being exposed to the delivery pressure the end of smaller area being exposed to the pressure in the casing between the plunger and the supply, means of regulating the stroke of said plunger, means of maintaining the plunger 120 against the delivery pressure until a predetermined point of said pressure is reached and means of regulating said predetermined point of said pressure.
- 90 11. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas the end of larger area being exposed to the delivery pressure the end of smaller area being exposed to the pressure in the casing between the plunger and the supply, means of regulating the stroke of said plunger, means of maintaining the plunger 125 against the delivery pressure until a predetermined point of said pressure is reached and means of regulating said predetermined point of said pressure.
- 95 12. An automatic injector comprising a casing with a supply adjacent to one end and a delivery adjacent to the other end, a liquid supply pipe communicating with the supply, a check valve therein, a plunger in the casing between the supply and delivery free to reciprocate therein and having ends of differential areas the end of larger area being exposed to the delivery pressure the end of smaller area being exposed to the pressure in the casing between the plunger and the supply, means of regulating the stroke of said plunger, means of maintaining the plunger 130 against the delivery pressure until a predetermined point of said pressure is reached and means of regulating said predetermined point of said pressure.

liquid supply pipe communicating with the supply, a check valve therein, a plunger in the casing between the supply and delivery free to reciprocate therein and having ends of differential areas the end of larger area being exposed to the delivery pressure the end of smaller area being exposed to the pressure in the casing between the plunger

and the supply, yielding means moving the plunger toward the delivery and means of regulating the amplitude of movement of the said plunger.
